UNITED STATES PATENT OFFICE.

EDWARD J. QUIGLEY, OF NEWARK, NEW JERSEY.

SOFT COLLAR.

1,199,303.

Specification of Letters Patent. Patented Sept. 26, 1916.

Application filed June 29, 1914. Serial No. 847,840.

To all whom it may concern:

Be it known that I, EDWARD J. QUIGLEY, a citizen of the United States, and a resident of Newark, in the county of Essex and State 5 of New Jersey, have invented certain new and useful Improvements in Soft Collars, of which the following is a specification.

This invention relates to collars, more particularly to soft or negligée collars, and the 10 objects of the invention are to provide a soft or negligée collar which when in use will have many of the advantages of a stiff collar without the use of celluloid strips or similar separate stiffening means, or without 15 the use of additional plies of cloth applied to the neck band about the button holes.

Further objects of the invention are to provide the collar with integral stiffening 20 means that in no way interfere with the appearance, comfort or laundrying of the collar.

Figure 1 is a perspective view of a collar made in accordance with the invention. Fig. 25 2 is a sectional view on the line 2—2 of Fig. 1. Fig. 3 is a sectional view on the line 3—3 of Fig. 1. Fig. 4 is a view showing the collar and extension tabs laid out flat.

In the present instance A designates the 30 top or outer portion and B the neck band or inner portion of the collar which is usually made of two or more plies of linen, silk or cotton sewn together and cut to form a turned down collar such as shown in Fig. 1.

In order to obviate starching the collar 35 to keep it upright when in use, folding tabs secured to the front and back of the collar are provided for accomplishing this purpose.

The front of the collar is supported by 40 means of a front extension tab C secured to the edge of one of the tabs D of the neck band. The front tab C is shaped to conform to the neck band tab D when the same 45 is folded back along the line E, as shown in Figs. 1 and 3, to support the front portion of the collar. The front tab C is provided with a suitable button hole F which registers with the button hole G when the 50 same is folded into position for use.

The back of the collar is supported by 55 means of a back extension tab H secured to the edge of the neck band adjacent the back button hole of the collar. The back tab H is arranged to be folded back along the line K, as shown in Figs. 1 and 2, to support the

back of the collar. The back tab H is provided with a button hole L, which overlaps a recess M in the neck band when the tab H is folded back in use. The recess M is 60 preferably made larger than the button hole L so as to permit of the easy insertion of the back collar button into the button hole L.

From the above it will be seen that it is a 65 very easy matter to starch the front and back extension tabs without starching the rest of the collar, and these tabs when starched and folded into position will hold the unstarched portions of the collar into shape and prevent their sagging.

Extension tabs such as described are far 70 superior to separate stiffening members for supporting the collar, as stiffening members are hard to keep in place and are otherwise objectionable. The same applies to additional plies of cloth, secured to the neck band about the button holes, which are to be starched without starching the rest of the collar, such collars are invariably starched all over by the laundries or they 75 are not starched at all, it being practically impossible to educate the ordinary laundry into properly starching a collar of this type. When, however, a collar is provided with extension tabs, in accordance with this invention, it is a very easy matter to get 80 laundries to starch only the tabs.

Of course, if desired, one of the tabs can 85 be omitted, but in an ordinary collar it is desirable to use both front and back tabs.

While the invention has been described 90 with particular reference to the details of construction, the same is not to be considered as limited thereto as many changes can 95 be made and still fall within the scope of the invention set forth in the following claims.

What I claim is:

1. A soft turned down collar provided 100 with an extension folding tab secured to the neck-band at the back, said tab being adapted to be starched, and being shaped to extend to the top of the collar to support the back of the same in proper position.

2. A soft turned down collar provided 105 with extension folding tabs at the front and back, adapted to be starched, said tabs having buttonholes therein and being shaped to extend to the top of the collar and to conform thereto to support the front and back 110 of the collar in proper position.

3. A soft turned down collar having an

enlarged opening for the collar button at the back, and an extension folding tab secured to the bottom of the neck band at the back and adapted to be starched, said tab having a buttonhole adapted to aline with said opening and being shaped to extend to the top of the collar to support the back of the same in proper position.

In testimony whereof I have signed this specification in the presence of two subscribing witnesses.

EDWARD J. QUIGLEY.
